UNITED STATES PATENT OFFICE

DOROTHY SHERRILL, OF MARSHFIELD, MASSACHUSETTS

DESIGN FOR A RAG DOLL

Application filed June 22, 1932. Serial No. 44,163. Term of patent 14 years.

To all whom it may concern:

Be it known that I, DOROTHY SHERRILL, a citizen of the United States, residing at Marshfield, county of Plymouth, and State of Massachusetts, have invented a new, original, and ornamental Design for Rag Dolls, of which the following description in connection with the accompanying drawing is a specification.

Fig. 1 is a front elevation, and Fig. 2 a fragmentary side elevation of a rag doll, showing my new design.

The essential feature of the new design consists in the fact that a member, projecting outwardly and downwardly, is fixed to the face of the doll above either eye in simulation of a drooping eyelid so that, as shown in the drawing, the eyes appear to be partially closed.

I claim:

The ornamental design for a rag doll, as shown and described.

DOROTHY SHERRILL.
